UNITED STATES PATENT OFFICE.

PACIFICO BORRA, OF WEST HOBOKEN, NEW JERSEY.

MEANS FOR DISSIPATING FOG.

Application filed December 19, 1924. Serial No. 757,025.

To all whom it may concern:

Be it known that I, PACIFICO BORRA, a citizen of the United States, residing at West Hoboken, in the county of Hudson and State of New Jersey, have invented certain new and useful Improvements in Means for Dissipating Fog, of which the following is a specification.

This invention relates to means for dissipating fog, and for signaling between ships or between a ship and the shore, in foggy weather. In carrying out the invention, I provide, on the forward end of a ship, a gas tank containing gas at high pressure and a burner connected to the tank and directed forwardly of the ship, and from which a flame can be projected a considerable distance in advance of the ship. The heat of this flame will dissipate the fog in its immediate vicinity so that a look-out or observer stationed beneath the burner will have a clear vision in advance of the ship for the distance to which the flame is extended, and I also provide a similar apparatus at the stern of the ship, with a burner pointing rearwardly, so that a flame may be projected for a considerable distance to the rear of the ship. This flame will dissipate the fog immediately surrounding it, and for a distance back of the ship equal to the length of the flame, enabling the lookout on a following ship to see the ship in advance. Thus, where two ships are equipped with the apparatus, and one is in advance of the other, the look-out on the ship at the rear will have the advantage of a clear vision through the space cleared of fog by the forward flame on the following ship and the rearward flame on the ship in advance. As a further means for dissipating fog, to enable the look-out to see in advance of the ship, I provide, immediately at the rear of the horizontal burner at the front of the ship, a gas tank containing gas under high pressure and a plurality of burners extending vertically from the tank by means of which a plurality of flames may be projected high in the air to dissipate the fog from the vicinity of the forward horizontal burner, and also to serve as a signal to other ships. These vertical burners are connected to the same gas tank, and they are controlled by independent valves, so that, if desired, one or more of the burners may be shut off and the flame from the remaining ignited burner, or burners, will

extend higher, enabling it to be seen at a greater distance from the ship. These vertical burners, being located back of the look-out, will not interfere with his view forwardly. 60

While the invention is particularly desirable on ships, it may also have use on land, particularly at lighthouses, for dissipating fog, and for signaling. 65

In the accompanying drawing,

Fig. 1 is an outline view of a ship, partly broken away, showing a fog penetrating and signaling apparatus mounted thereon;

Fig. 2 is a central vertical section through the apparatus at the forward end of the ship; 70

Fig. 3 is a top plan view of the gas tank shown at the left in Fig. 2; and

Fig. 4 is a section on the line 4—4 of Fig. 2. 75

Referring to the drawing, *a* indicates a ship or other vessel, upon the forward end of which is mounted a suitable structure *b*, for supporting the fog-dissipating and signaling apparatus above the upper deck of the ship, and *c* indicates a structure for supporting fog-dissipating apparatus at the stern of the ship. 80

The apparatus at the front of the ship comprises an outer tank 1, open at the top, an inner tank 2, also open at the top and resting upon the bottom of the outer tank, and a bell 3, extending over the inner tank and fitting gas-tight against the bottom of the outer tank. A guide rod 4 extends upwardly through the bottoms of the outer and inner tanks, at their centers, and a tube 5, in the inner tank, fits over this rod and carries a plurality of pans 6, within which calcium carbide may be placed. A water tank 7 is mounted on an upright pipe 8, and this pipe extends below the tanks 1 and 2, thence upwardly, as shown at 8^a, between the tank 2 and bell 3, and thence downwardly a short distance into the inner tank 2, as shown at 8^b. The upper end of the pipe 8 is closed by a cap 8^c. A branch pipe 8^d connects the pipe 8 with the lower part of the water tank, and a valve 9 is provided in this branch for admitting or cutting off the supply of water from the water tank to the pipe 8. The bell 3 is held firmly in its place by metal bars 10, detachably secured to the wall of the outer tank 1 and extending over the top of the bell. By taking off the bars, the bell may 100

110

be removed and the tube 5, with the pans 6 attached, may then be removed when it is desired to empty the latter, a T 5^a being provided on the top of the tube and serving 5 as a handle for lifting the tube and pans.

When water is admitted from the water tank through the pipe 8 to the tank containing the carbide, it will be evident that acetylene gas will be generated. By opening the 10 valve 9, a quantity of water sufficient to cause the generation of a large quantity of gas may be admitted, and the valve 9 may then be closed. This gas, at high pressure, will fill the bell and the upper part of the 15 tank 2. The outer tank or casing 1 is provided as a safety device, to divert any gas escaping from the bell upwardly. This tank holds a volume of water 11, which prevents any back flare to the bottom of the bell 20 in case gas, escaping at that point, becomes ignited from the burners above. Any escaping gas would be spread out in bubbling up through the water instead of flowing up in a steady stream, and in case the gas so 25 escaping should become ignited, the water would prevent the flames from reaching the lower end of the bell.

A blow-off pipe 12 extends through the top of the bell and is controlled by a valve 30 13, which may be operated by a cord or chain 14, extending to a point where it may be easily reached by the look-out who will be stationed in a crow's nest *g*, conveniently mounted at the front of the supporting 35 structure *b*. This valve may be opened to relieve the pressure in the bell when desired. A pipe 15 extends through the top of the bell and thence forwardly of the ship for a suitable distance and is provided at its forward 40 end with a suitable burner 16. The flow of gas through this pipe is controlled by a valve 17, which may be operated by a cord or chain 18, extending to a point where it may be conveniently reached by the look-out. For igniting the gas, a suitable electric igniter, indicated conventionally at 19, is arranged adjacent the end of the burner and is connected to a battery 21 by conductors 22 and 23, the latter containing a switch 45 24 which may be operated by the look-out from his position in the crow's nest.

In the operation of the apparatus thus far described, assuming the ship to be surrounded by a dense fog, the operator will pull the 50 chain 18, opening the valve 17, and gas will be projected at high velocity through the pipe 15 and burner 16, in advance of the vessel. By closing the switch 24, this gas will be ignited and a flame, the length of 55 60 which will depend upon the gas pressure, will be projected horizontally in advance of the ship. This intensely hot flame will disperse the fog in the vicinity of the flame, throughout its length and for some distance 65 beyond, owing to the heat which is carried

forward from the end of the flame. Through this space which is cleared by the flame, the look-out will have a clear vision which, of course, enables him to see an object in advance, such as another ship, sooner than he would if the flame were absent. 70

Immediately at the rear of the apparatus just described for projecting a forward flame, is a gas generating plant *e*, the same in all respects as the plant previously described. On the bell 3 of this latter plant are mounted three vertically arranged burners 25, 26 and 27, controlled by valves 28, 29, and 30, respectively, these valves being operable, respectively, by cords or chains 31, 32, and 33, extending to points adjacent the crow's nest. An igniter 34 is arranged adjacent one of the burners and connected by wires 35 and 36 to a battery 37, a switch 38 being arranged in the wire 36 at a point convenient to the look-out. 80 85

It will be evident that if the three valves, 28, 29, and 30, are opened and the burner 27 is ignited by closing the switch 38, the other two burners will be ignited by reason of their proximity to the first mentioned burner. It will also be evident that when the three valves are opened, the flames will be projected vertically to a height dependent upon the gas pressure, and that if say two of the valves are closed, putting out two of the burners, the flame of the other burner will be projected much higher than before by the gas pressure. Ordinarily, when the forwardly extending burner 16 is ignited, in a thick fog, the several burners 25, 26, and 27 will also be ignited and these will dissipate the fog in the vicinity of the look-out. As the look-out will have his back turned to these burners and will be shielded from the direct glare of the burners by the forward tank and supporting apparatus, the flame will not interfere with his vision forward. 90 95 100 105

At the rear of the ship, the apparatus indicated at *f*, in Fig. 1, is the same in all respects as the apparatus shown at the right in Fig. 2, but the burner 39 extends rearwardly from the gas generating apparatus so as to project a flame rearwardly from the ship. This apparatus is intended to be kept constantly burning during heavy fogs and its function is as a signal to other ships, and also to clear the atmosphere of fog for a distance at the rear of the ship equal in length to the flame projected, or to such further distance as the heat of the flame may be projected. If a following ship having a forward burner, enabling the look-out to see ahead of the ship for the distance which is cleared by the forward flame, approaches a ship in advance, the rearwardly projected flame on the latter ship will clear the fog for a distance equal to the length of the latter flame, and the look-out or observer will be enabled to see the forward ship 110 115 120 125 130

sooner than if the ships were without the burners.

What I claim is:

- 5 1. The combination with a ship, of means at the forward end of the ship for projecting a flame forwardly, and means immediately at the rear of said first mentioned means for projecting a flame upwardly.
- 10 2. The combination with a ship and gas producing means, of burners at the forward end of the ship for projecting a flame forwardly, and burners immediately at the rear of said means for projecting a plurality of flames upwardly.
- 15 3. The combination with a ship and gas producing means, of burners at the forward

end of the ship for projecting a flame forwardly, burners immediately at the rear of said means for projecting a plurality of flames upwardly, and means for independently controlling the flow of gas to said latter burners. 20

4. The combination with a ship, of means at the forward end of the ship for projecting a flame forwardly, means, immediately 25 at the rear of said first mentioned means, for projecting a flame upwardly, and means at the rear end of the ship for projecting a flame rearwardly.

In testimony whereof I hereunto affix my 30 signature.

PACIFICO BORRA.
